UNITED STATES PATENT OFFICE.

ELIAS W. SEYMOUR, OF CENTER LISLE, AND GEO. W. GREGORY, OF BINGHAMTON, N. Y., ASSIGNORS TO SAID GEORGE W. GREGORY.

IMPROVEMENT IN HAY-ELEVATING FORKS.

Specification forming part of Letters Patent No. 38,872, dated June 9, 1863.

To all whom it may concern:

Be it known that we, ELIAS W. SEYMOUR, of Center Lisle, and GEORGE W. GREGORY, of Binghamton, both of the county of Broome and State of New York, have invented a new and Improved Mode of Constructing Hay-Elevating Forks, known as the "Revolving Elevating Hay-Fork;" and we do hereby declare that the following is a full and exact description thereof.

To enable others skilled in the art to make and use our invention, we will proceed to describe its construction and operation, reference being had to the annexed drawings.

We take a piece of hard wood for the head A, about two feet long, three by three, and turn a groove, B, around the center of said head, about two inches wide and one-quarter of an inch deep, for the purpose of receiving a piece of band-iron of a corresponding size with said groove, for the purpose of attaching the head of the fork to the handle C. We then bore the holes in said head for the purpose of receiving the tines D. Said tines are made of either round or square iron or steel, about sixteen inches long by five-eighths thick, and can also be made either crooked or straight tines. We then take a stick about two feet long and form the handle C, fitting the lower end to the groove in the center of the head. We then take a piece of band-iron of the size to fit the groove in the head of the fork, and of sufficient length to extend around the head and up both sides of the handle—say six inches on each side—and clasp it around the head in said groove, and secure it to the handle by bolts or screws, which when so secured forms the band or box in which the said fork revolves. We then fit a piece of iron or wood to the front part of the head, which receives the two center tines, and extends around the front part of the head and up in front of the handle—say six inches—which iron or wood forms both a brace and the latch E, which prevents the fork from revolving when loaded for elevation. We then mortise a hole in the handle directly over the top of the latch, for the purpose of

fastening a lever-spring catch, which lever-spring catch F drops over the top of the latch and firmly secures the same. We then attach to the lever part of said spring-catch a cord, which passes down the back side of the fork-handle, by means of which the fork is relieved from its load when required. We then take a piece of rope, G, about five feet long and attach each end either to the upper corners of the latch or brace E, or to the ring-staples J J, which is put in the front part of the head near the two outer tines. When the said rope G is attached to the brace E it is extended up the front part of the fork-handle to within one inch of the staple H, which is put in the front part of the fork-handle, near the top, through which the hoisting-rope passes down, and is fastened to the center of said rope G, by which means the fork is kept in its position to retain its load. The said rope G, when attached to the latch or brace E, or to the head of the fork by any other device at a given point above the head, forms a double brace when acted on by the hoisting-rope. When said rope G is attached to the ring-staples J J it must be passed around the back part of the head, and then up the front part of the handle to receive the hoisting-rope, as above described. The hoisting-rope, passing down through the ring-staple H, and being attached to the center of the rope G, keeps the fork from tipping sidewise, and in the right position for elevating and retaining its load. The said rope G, when attached to the corner of the latch or brace E, causes the fork when relieved from its load to take its natural position to be secured by the latch.

What we claim as our invention, and desire to secure by Letters Patent, is—

The peculiar construction and combination of the head A, handle C, latch E, lever-spring catch G, and staple H, as and for the purpose herein described.

ELIAS W. SEYMOUR.
GEO. W. GREGORY.
